United States Patent Office.

JAMES M. JONES, OF COMMERCE, MISSOURI.

Letters Patent No. 97,927, dated December 14, 1869.

IMPROVEMENT IN SAW-SETS.

The Schedule referred to in these Letters Patent and making part of the same.

To all whom it may concern:

Be it known that I, JAMES M. JONES, of Commerce, in the county of Scott, and in the State of Missouri, have invented new and useful Improvements in Saw-Sets; and do hereby declare that the following is a full, clear, and exact description thereof, reference being had to the accompanying drawings, and to the letters of reference marked thereon.

The nature of my invention consists in the construction of a machine for gauging or setting the teeth of saws, and in the arrangement of the devices hereafter set forth and explained.

Figure 1 is a side view of my machine.

Figure 2 is a plan view of the same.

Letter A represents the base, from which there rise four standards, two of which support the two shafts connected with the markers, while the others uphold the table.

The rear standard B is slotted about four-fifths of its whole length, in which the two slides C, holding the ends of the shafts D, play up and down.

These sliding bearings can be retained in their places by means of the screws E, and are placed at such a height as to regulate the markers for the ordinary saws.

The standard F has two slots cut in it, in which there are also placed two movable bearings for the shafts D, but these bearings do little more than tilt up and down, in order to regulate the markers.

Extending between the two standards, B and F, are the two shafts D, by means of which the markers G are operated.

Each of these shafts is provided with two movable bearings, C and H, so that the two markers can be made to vary, so as to suit larger or smaller saws.

These markers consist of two cylinders, tapering toward the front end, the surfaces of which are grooved, so as to mark the saws as they are passed between. The grooves are large upon the rear end, and small upon the front one, so as to suit different-sized saws.

By moving the outer ends of the shafts near together, the largest cogs only will mark, but by moving them far apart, the smallest ones only mark.

Extending on a level with the point at which the two markers gear or meet, there is a table, L, which is supported by the standards I. In the middle of this table there is an opening made, large enough to allow the markers to come in contact with each other.

Upon each side of the markers there is placed a gauge, N, so as not only to guide the saws while being drawn through, but also to assist in gauging the markers.

The motive-power is applied to the ends of the shafts D, which extend out, back of the standard B; then, while the markers are revolving, the saw-blade is passed in between them.

Having thus described my invention,

What I claim, and desire to secure by Letters Patent, is—

1. The two shafts D, when provided with the movable bearings C and H, and when used to operate the markers G, substantially as and for the purpose described.

2. The slotted standards B and F, in combination with the movable bearings C and H, and shafts D, when used in the manner and for the purpose described.

3. In combination with the markers G, the table L and guides N, substantially in the manner and for the purpose specified.

4. The arrangement of slotted standards B and F, movable bearings C and H, markers G, table L, and gauges N, when all are combined to operate in the manner and for the purpose set forth.

In testimony that I claim the foregoing, I have hereunto set my hand, this 27th day of March, 1869.

JAMES M. JONES.
